[57] CLAIM

The ornamental design for a tennis training device or the like, as shown.

DESCRIPTION

FIG. 1 is a side elevational view of a tennis training device or the like showing my new design;

FIG. 2 is an enlarged left side elevational view of the upper portion thereof;

FIG. 3 is an enlarged right side elevational view of the lower portion thereof, partly broken away for clarity of illustration; and

FIG. 4 is an enlarged cross-sectional view taken along line 4—4 of FIG. 1.
